NAME PLATE

James E. Nichols, Taunton, Mass.

Application April 19, 1937, Serial No. 137,625

6 Claims. (Cl. 40—144)

This invention relates to name plates, and especially those used for caskets or coffins.

One object of my invention is to provide a plate which is adapted to receive separate letters, figures or other characters in any desired combination, and which may be removed or changed at will. Another object is to provide separate letters or other characters for said plate of new and original construction. Still another object is to provide such a plate and letters so simple and efficient in construction and combinational arrangement that a layman can assemble them on said plate and form a name or other designation readily without special training or instruction, and produce an artistic appearance, and which letters will remain in the assembled position even though the plate is shaken or moved about.

I am aware that others have made name plates to receive separate characters along similar lines, and it has been my particular object to so improve said name plates that they will become more desirable and advantageous to use.

The foregoing and other objects which will appear as the nature of the invention is better understood, may be accomplished by a construction, combination and arrangement of parts such as is disclosed by the drawing and specification. The nature of the invention is such as to render it susceptible to various changes and modifications, and, therefore, I am not to be limited to said disclosure; but am entitled to all such changes therefrom as fall within the scope of my claims.

In the drawing:

Figure 1 is a front elevational view of my name plate.

Figure 2 is a sectional view taken on the line 2—2 of Figure 1.

Figure 3 is an enlarged sectional view taken on the line 3—3 of Figure 1 showing the position of the cord lines in the character members.

Figure 4 is an enlarged, fragmentary, front elevational view to more clearly illustrate the relation of the holding cords of the plate to the character member held thereby.

Figure 5 is a fragmentary front elevational view of a modified form of my plate.

As illustrated, I provide a plate or backer 12 which is preferably made of metal and oblong in shape. It has holes 13 therein whereby it may be nailed or screwed to a casket or other supporting member. Adjacent each end of said plate 12 are two holes 14, one above the other, through which a cord 15 is strung. Said cord is preferably a single length and extends from the back end of said plate through a said cord hole 14 hori-

zontally across said plate 12 to and through a said cord hole 14 in horizontal alinement with the first-mentioned cord hole, then vertically in back of said plate to the cord hole 14 in vertical alinement therewith, thence horizontally across said plate 12 to and through a said cord hole 14 in vertical alinement with the first-mentioned cord hole where said cord started, and the two loose ends are tied or secured as at 16 to thereby securely and firmly hold said cord in place. I find it preferable to make said cord 15 of material having some elasticity such as catgut, or silk cord is suitable, and preferably of the same color shade as the characters 18 or plate 12. I have designated the upper front line of said cord as 15a and the lower front line of said cord as 15b, and, of course, these cords could be two separate pieces. Said cord is drawn firmly across the front of said plate 12 to avoid slackness.

The writing or designation on said plate 12 is formed by means of separate letter or character members 18, in the bottom and top of which horizontal channels 19 are formed which extend inwardly into the body of said members 18, the sides of which channels 19 preferably extend straight downwardly, as it is desirable to avoid locking or wedging said cord 15 at the bottom of said channels 19.

In order to hold said character members 18 more securely in place the cord lines 15a and 15b are spaced apart a distance slightly less than the distance between the bottom of the upper channel 19 and the top of the lower channel 19 in said characters 18, with the result that when said character members 18 are in place between said cord lines 15a and 15b there is a slight stretching or tension of said cord lines which provides sufficient friction on said character members 18 to keep them from moving or otherwise being displaced. This feature is best illustrated in Figure 4 of the drawing.

In the modification illustrated in Figure 5 of the drawing there is provided a plate having provision in the form of numerous holes 21 spaced apart whereby said cord 15 can be kept from view at the front of the plate 12. Said holes 21 extend through said plate 12, and are large enough to accommodate said cord 15, which is so strung on said plate 12 that it is at the front thereof only where a character member 18 is to appear, and all other portions are at the back of the plate as illustrated by the dotted lines in Figure 5 of the drawing. In this modification the upper line of cord where it appears at the front is given the numeral 22 and the lower line is 23, and

it will readily be seen that by lacing of said cord 15 through the said holes 21 so that it is at the front of the plate only where the top and bottom of the character members 18 are, that said cord 15 need not be visible in front view at all. Said 5 holes 21 are preferably spaced the same distance apart; which space does not exceed the width of said character members, and preferably is less. The construction of said plate 12 and the association of said character members 18 is the same 10 as shown in Figure 1 of the drawing except for the two lines of said holes 21 and intermittent appearance of said cord at the front of said plate.

What I claim is:

- 15 1. A name plate comprising in combination a plate and separate character members held thereto, the main body of said character members being formed to the shape of the particular characters they represent, two cord lines spaced apart fastened to and extending part way across said plate, said character members having channels in their upper and lower sides extending vertically into the body of the characters, said cord lines extending into said channels whereby 20 said character members are held in position in association with said plate.
- 20 2. A name plate comprising in combination a plate and separate character members in association therewith, said plate having holes therein 25 extending from front to back, a resilient cord a portion of which is at the back surface of said plate and portions of which extend through said holes and partly across the front of said plate and form two lines spaced apart, said character 30 members having channels therein at the top and bottom thereof and extending into the body thereof, said cord line extending into said channels whereby said character members are held in position in association with said plate.
- 30 3. A name plate comprising in combination a plate and separate character members in association therewith, said plate having holes therein 35 extending therethrough, two resilient cord lines spaced apart and connected thereto and extending firmly part way across the front of said plate, the upper and lower portions of said character members having channels therein intermediate the front and rear faces thereof, said cord lines extending into said channels, the normal distance 40 between said cord lines being less than the distance between the inward extremities of said upper and lower channels in said character members, whereby said character members are held under tension by and between said cord lines.
- 45 4. A name plate comprising in combination a plate and separate character members held thereto, said plate having holes therein extending therethrough, a cord extending from the back of said plate through a said hole and across 50 a portion of the front of said plate and through another said hole to the back of said plate and

extending for a distance along the back of said plate and then through another said hole and then extending across a portion of the front of said plate and through another said hole to the back of said plate, said cord being secured at 5 the back of said plate, the portions of said cord extending across the front of said plate being spaced apart, said character members having a channel at the top thereof extending downwardly into the body of said members and a 10 channel at the bottom thereof extending upwardly into the body thereof, the two sections of said cord at the front of said plate extending through said channels whereby said character members are held in position in association with 15 said plate.

5. A name plate comprising in combination a plate and separate character members held thereto, said plate having holes therein extending therethrough, a cord having one end extending from the back of said plate through a said hole and firmly across a portion of the front of said plate and through another said hole to the back of said plate and extending for a distance vertically along the back of said plate and then 20 through another said hole and then extending firmly across a portion of the front of said plate and through another said hole to the back of said plate, the two ends of said cord being secured at the back of said plate, the portions of 25 said cord extending across the front of said plate being spaced apart, said character members having a channel at the top thereof extending downwardly into the body of said members and a channel at the bottom thereof extending upwardly into the body thereof, the two sections of said cord at the front of said plate extending through said channels and contacting said body at the terminating points of said channels whereby 30 said character members are held in position 35 in association with said plate.

6. A name plate comprising in combination a plate and a separate character member held thereto, said plate having a plurality of holes extending horizontally in two lines across a portion of said plate at a distance apart not exceeding the width of said character member, a cord connected to said plate forming two cord lines each extending from the back of said plate through a said hole horizontally across the front of said plate to another said hole adjacent thereto, and extending therethrough to the back of said plate, a portion of said cord at the front of said plate being opposite said character member, said character member having channels at 45 the top and bottom thereof, said cord lines extending into said channels whereby said character member is held in position in association with 50 said plate.

JAMES E. NICHOLS. 60
